UNITED STATES PATENT OFFICE.

OMAR A. WHEELER, OF PORTLAND, OREGON, ASSIGNOR TO WHEELER AUTOMATIC MACHINE COMPANY, OF PORTLAND, OREGON.

CUFF-MAKING MACHINE.

Application filed May 10, 1923. Serial No. 638,151.

My invention relates to my previously invented machine for making cuffs automatically as described in the Letters Patent of the United States granted to me June 3, 1919, No. 1,305,510.

This application is filed as a continuation in part of the application for Letters Patent filed by applicant January 27, 1920, Serial No. 354,478, entitled Cuff making machine, for the purpose of protecting by Letters Patent the invention set forth in said previously filed application and applicant's later improvements on said invention.

The object of my present invention is to replace those devices in my said machine provided in the latter for arranging and holding the cuff material preparatory to sewing by other devices suitable for the making of the present standard type of attached cuffs for shirts. The type referred to is that diagrammatically shown with respect to the arrangement of the plies by Fig. B of the accompanying drawings, and with respect to the formation of the cuff by the fragmentary perspective Fig. E both figures referred to appearing on Sheet 7.

In short this type of cuff consists of an outer blank or piece 80 cut to the desired shape of the cuff and an inner blank or piece 81, these pieces being laid in the trays of the carriage and thence become arranged in the "work holder" of my machine as shown in Fig. A. These pieces are then fastened together by a seam 82 extending all around on three sides. These pieces are then turned inside out and are further fastened together by marginal stitches 83, the stitches 82 being made while the plies of the cuff are gripped in the work holder and the stitches 83 being made while the cuff is held there by the fuller bars of my machine having been removed. These details are hereafter more fully described.

The outer piece 80 has an inward edge fold as 84 which is formed in the work holder and the inner piece 81 has a projecting lip as 85. This projecting lip is stitched to the inner face of the shirt sleeve 86 as diagrammatically shown at 87 in Fig. C. The cuff plies are then arranged as shown by Fig. D and finally the cuff is finished by a second seam indicated by the dotted

line 88 in Fig. D. The latter two operations are not performed by my machine which merely forms and sews the cuffs ready for sewing to the end of the shirt sleeve. The type of cuff made by my present invention has heretofore been made entirely by hand.

My present invention produces this cuff by automatic devices which comprise the following elements:

In a machine of the character described, a carriage, trays, supported by the carriage, for holding the blanks, such trays being initially positioned spaced apart in horizontal planes, means for forming a downturned fold on the forward edge of the blank carried by one of said trays, means for advancing one tray relatively to the other, thereby to align the trays vertically, a work-holder comprising upper and lower vertically movable parts, means for moving such parts from each other, means for moving the carriage forward while the upper and lower parts of the work-holder are spaced from each other, means for gripping the forward edges of the blanks, means for producing a fullness in one of said blanks while in the work-holder, means for moving said work-holder parts together after the trays have been removed from between them, thereby holding the blanks in the work-holder for the sewing of the edges of the blanks together, means for withdrawing said fullness-producing means after the blanks have been clamped by the work-holder, the operation of said devices being timed relatively to each other.

These devices and associated mechanisms are illustrated by the remaining figures of the accompanying drawings, viz:

Fig. 1, Sheet 1, represents a perspective view, partly in section, of those parts of my improved machine to which my present invention relates:

Fig. 1^a, Sheet 1, is a partial perspective view of the "work-holder" of my machine as seen from the rear end, thus the right end with respect to Fig. 1, said figure being taken approximately in the direction of the arrow 1^a in Fig. 1;

Fig. 2, Sheet 2, is a longitudinal sectional detail of the upper part of the carriage, and

of the trays carrying the blanks from which the cuff is to be made: the carriage being shown in its initial position, said figure being taken in the direction of the arrow 2 in Fig. 1;

Fig. 2^a, Sheet 5, is a perspective view of the two trays and a fragment of the carriage; the upper tray in this figure has been moved horizontally beyond its initial position, to completely uncover the lower tray;

Fig. 2^b, Sheet 5, is another longitudinal sectional detail of the upper portion of the carriage and of said trays; and this figure also shows in part the devices provided for forming the fold 84 shown in Figs. A to E; the devices as here shown are positioned ready to form said fold;

Fig. 2^c, Sheet 5, shows a sectional detail of the lower tray, (g) and the adjacent portion of the carriage;

Fig. 3, Sheet 2, is a fragmentary, longitudinal, central section through the trays and workholder of my machine with the carriage in its advanced position, thus having introduced the trays into the work-holder;

Fig. 4, Sheet 2, is a sectional detail of the work-holder of my machine; this figure illustrating the further operation of devices of the work-holder;

Fig. 4^a, Sheet 2, is a fragmentary sectional detail of the lower part of the work-holder illustrating the action of the clamp carried by such part;

Fig. 4^b, Sheet 2, shows a fragmentary detail of the clamp in the lower part of the work-holder;

Fig. 4^c, Sheet 2, is a fragmentary detail of the reciprocable cross-head of the lower part of the work-holder;

Fig. 5, Sheet 2, is a larger scaled detail of the work-holder, showing the upper and the lower parts thereof as brought together and clamping the blanks placed in the work-holder by the trays, ready for sewing; the blanks are seen spaced apart to give the desired fullness, and the fuller is seen between the blanks;

Fig. 5^a, Sheet 2, is a detail of the said upper blank-carrying tray and of the upper part of the work-holder, and illustrates the action of the means provided for lifting the forward edge of the blank in the upper tray, so as to position such edge for being clamped by the clamp of the upper part of the work-holder;

Fig. 6, Sheet 1, shows, diagrammatically, part of the mechanism by which the work-holder is opened and closed;

Fig. 7, Sheet 3, is a rear, sectional elevation of the work-holder, as viewed in the direction of the arrow 1^a in Fig. 1;

Fig. 8, Sheet 3, is a fragmental plan section of the work-holder, taken approximately on the line 8-8 of Fig. 7, and illustrates the action of the fuller-member;

Fig. 9, Sheet 3, shows a plan of the lower box-like part of the work-holder, the fuller member being seen as inserted in said part and expanded to form the fullness in the lower blank, which is shown in section by 70 80 in Figs. A, B, C, D and E on Sheet 7;

Fig. 10, Sheet 3, shows a fragmentary detail, in rear elevation, of the fuller-member, as viewed in the direction of the arrow 10 in Fig. 9;

Fig. 11, Sheet 6, shows a portion of the upper part of the carriage and of the trays taken substantially in the direction of the arrow 2 in Fig. 1; this view illustrating the initial position of the devices provided for forming the fold 84 (see Figs. A to E) in the blank carried by the lower tray;

Fig. 12, Sheet 6, shows a fragmentary detail of the means for operating said devices of Fig. 11 which are here also shown in their initial position;

Fig. 13, Sheet 6, illustrates the next phase in the action of such means shown in Fig. 12;

Fig. 14, Sheet 6, illustrates the positions 90 assumed by "the ironing bar" and "the presser" which form said fold 84, said view being taken on the same line as Fig. 11;

Fig. 15, Sheet 6, shows the final positions of the devices forming said fold, said view 95 being taken on the same line as Fig. 11;

Fig. 16, Sheet 6, is a detail of the parts pointed to by the arrow 16 in Fig. 12 looking in the direction indicated by the arrow;

Figs. 17, 17^a, 17^b, 17^c and 17^d, Sheet 3, 100 show details of the construction and operation of the clamp of the upper part of the work-holder;

Fig. 18, Sheet 1, shows a fragment of the cuff produced, illustrating its appearance 105 after having been turned right side out;

Fig. 19, Sheet 4, shows a diagrammatic top view of the lower part of the work-holder, and of the fuller member, said view 110 being taken substantially on the same line as Fig. 8;

Fig. 20, Sheet 4, is a diagrammatic, vertical section thru the workholder, similar to Figs. 3 and 4 except that this section illustrates the position of the parts after the fuller member has been withdrawn, in advance of the insertion of the mechanism for turning the cuff right side out;

Figs. 21 and 21^a, Sheet 4, are further 120 details of the "ironing bar" and devices for forming said fold 84;

Fig. 22, Sheet 7, shows a sectional detail, in perspective, of the lower tray of the carriage and associated devices;

Fig. 23, Sheet 8, shows a side elevation 125 of my machine looking at the same side shown in Fig. 1; and

Fig. 24, Sheet 8, is a transverse sectional view through the fuller member shown in 130

connection with the workholder in Fig. 1^a, this figure being taken substantially along the line 24—24 in that figure. Figs. A, B, C, D, and E, Sheet 7, diagrammatically show the steps in the formation of a cuff, progressively.

My machine comprises a base *a* supporting pieces *b*, the opposed faces of which are adapted as at *d* to support a reciprocable carriage *c*. Motion is imparted to the carriage by a rod *e* fastened at one end to a lug *e'* of the carriage, see Fig. 3, and having operative connection with a cam located within the base; the cam being adapted to reciprocate the carriage, as herein-after described.

The function of the carriage is to arrange the blanks of which the cuff is to be made, and to introduce them into the "work-holder." These blanks are placed in the two trays *f* and *g* provided on the carriage; the lower tray *g* carrying the ply which is to form the outer piece or facing represented by 80 in Fig. A, and the upper tray carrying the ply which forms the inner piece 81 in Fig. A. Note the Figures A to D represent the cuff after having been turned right side out, while all the preliminary work is done by my machine before the cuff is turned; hence the ply parts appear reversed. If the cuff is to be made with a lining either or both of the trays may carry the lining piece or pieces.

The upper tray *f* is rigid on the carriage while the lower tray *g* is automatically moved forward under the upper tray during the forward travel of the carriage, see Figs. 2 and 3.

The portion *c*² of the carriage is provided with lugs *h* in which is journaled a shaft *j*. On one end of this shaft is fixed a pinion *m*, and on each end is fixed a pinion *m*². The pinion *m* meshes with the rack *b'* provided on one of the pieces *b* of the frame, and the pinions *m*² mesh with the rack faces *i* of the undersides of the side bars *h*, *h'* of the carriage *h*². The lower tray *g* is provided with arms *g'*, *g''*, which are hinged at their ends as at *h*³ between said side bars of the carriage *h*². See Fig. 2^a. The lower tray *g* is slidably held by its side bars *h'* in the guideways *l* of the carriage portion *c*².

The pinions *m* and *m*² are so proportioned that with the movement of the carriage forward the lower tray *g* will be moved at such speed as finally to be positioned directly under the upper tray *f* as shown in Fig. 3. In the lower tray *g* a U-shaped piece *o* is loosely held by two pins *o*²; see Fig. 2^a, said piece tends to lift the blank 80 so that it can be gripped by the sides of the work-holder parts.

In the upper tray *f* is secured a flexible and rockable plate *p*, provided with arms

p' as shown in Fig. 1, by which it is fastened in place. This plate *p* is of angular cross section, and fulcrums on its rib *p*³, (see Fig. 5^a) so that pressure on its edge *p*² will raise its edge *p*⁴; the purpose of which action is to grip the blank and to hold the piece of which the cuff is made up snugly so as to permit the clamping action of the hook 16. The plate *p* in the upper tray *f* and the piece *o* in the lower tray *g* also function to introduce the pieces or blanks carried by these trays, properly into the "work-holder", as hereinafter described.

As is shown in Fig. 2^a, *u* and *u'* are spring arms secured to the frame *h*² of the lower tray and are provided with heads *u*², the upper parts of which are adapted to extend over the cross rib *g*² of the lower tray *g* for bearing on the bottom of the latter, and in so doing holding the blank placed in this tray in place (see Fig. 2). The carriage portion *c*² is provided with grooves *x* for the heads *u*² of the spring arms *u* to move in when the lower tray is moved forward. When the lower tray is in its initial position said heads of the spring arms *u* will rest on collars *j*² provided on the shaft *j* as shown in Fig. 1, thereby raising said heads as shown by dotted outline in Fig. 2, so as to permit the placing of a blank in the lower tray. When the lower tray is moved forward the heads *u*² of the spring arms *u*, *u'* will drop from said collars *j*² into said grooves *x*, and thus bear on and hold the blank in place. During the continued forward travel of the carriage, the spring arms *u* will pass over the transverse cavity *c*³ of the carriage portion *c*², and finally climb on the surface *y*², as shown in Fig. 3, thereby lifting the heads of the spring arms *u*, *u'* 105 and thus releasing the blank from the lower tray.

v, *v'* are springs bearing on and tending to depress the lower tray *g*. See Fig. 1.

The fold 84 in the blank 80 carried by the lower tray is formed by the following devices:

An ironing bar *q*, and a presser *r* are carried by compressible rods *s*, *s'* over the depression *c*³ of the carriage portion *c*². The upper ends of the rods *s*, *s'* are reduced as at *s*² to provide shoulders for carrying sleeves *s*³, provided with heads at their upper ends. On the sleeves *s*³ are slidably mounted sleeves *s*⁴, which are integral parts of the ironing bar *q*, as more clearly shown by Fig. 21. On the sleeves *s*⁴ are mounted split collars *s*⁵, shown in Fig. 21^a. The sleeves *s*⁴ and the collars *s*⁵ are provided with flanges or shoulders, between which are coiled springs *s*⁶; see Fig. 11. Said heads of the sleeves *s*³ are provided with lugs *s*⁷ by which are rotatably supported the ends *r*² of the presser *r*. The journal ends of the latter extend beyond the lugs *s*⁷ and have 120 125 130

rigidly mounted thereon crank-arms 4 (see Fig. 12) which are connected by links t and t' with the bell-crank 3. The bell-crank 3 is pivoted at 117 on the rods s, s' .

6 The fold 84 of the blank 80 is formed in the lower tray g while in its initial position. First the bell-crank 2^b is actuated to depress the rods s, s' , part way from their position indicated in Fig. 11 to the position 10 indicated in Fig. 14, thereby bringing the ironing bar g down on the forward edge of the blank 80. The ironing bar g will now rest on the surfaces 90 of the lower tray, and hence has no further motion, but 15 the rods s, s' will be pulled down still further by the bell-crank 2^b, and simultaneously the bell-crank 3 is rocked so as to move the links t and t' up and rock the crank arms 4, and therewith the presser r , into its position in Fig. 14, and then move said links 20 down again, thereby bending the projecting edge of the blank 80 down; then swing the presser r to the left and causing it to bend the said projecting edge back and produce 25 the fold 84, as shown in Fig. 15. The bell crank 2^b is now so operated as to raise the rods s, s' and cause the lip 91 of the presser r to press the fold 84. The ironing rod g is electrically heated by means inserted in 30 the hole g^2 , of which heating means g^3 and g^4 , Fig. 1, indicate the terminals for connecting to a source of electricity.

The fold 84 of the blank 80 having been 35 formed the bell-cranks 2^b and 3 are next so operated as to permit the presser r to swing outward away from the foot 92 of the ironing bar g , and then ironing bar and presser resume their initial positions as shown in Fig. 11, thereby clearing the lower tray so 40 that it may be moved forward. That is to say, the carriage c , in being moved forward, effects the rotation of the pinion m , on the shaft of which are mounted the pinions m^2 as mentioned; and the latter engaging with 45 the rack faces i on the under sides of the side arm h, h' of the frame h^2 cause the forward movement of the lower tray g .

The bell cranks 2^b and 3 are operated 50 relatively with each other, to effect said operations, by the cam mechanisms herein-after described.

Upon the trays having been moved into the work holder the V-shaped ridge 77 on the plate 6^c of the upper part of the work-holder will bear on the edge p^2 of the plate p thereby tilting the latter on its fulcrum rib p^3 into its position in Fig. 5^a, thus lifting the forward edge of said plate and the blank lying on it, in position for the forward edge of the blank to be clamped by the clamp of the upper part of the work-holder as will be later explained.

The work holder is shown in its open 60 position in Fig. 3, and in its closed position in Fig. 4. It consists of an upper part 6,

and a lower part 7. It functions to hold the blanks of the cuff together during the sewing operation, and in such position that the blank carried by the lower tray may be given the required fullness by the fuller-member, in order to permit the inverting of the cuff as hereinafter described.

The upper part 6 of the work holder consists of a plate 6^c secured to a piece 6^d which is carried by rods 6^a sliding in bearings, 6^b supported from the portion 93 of the frame 94. See Figs. 1 and 6. On the frame portion 93 are journal bearings 95, one of which is shown in Fig. 1, the other being broken away, said bearings rotatably supporting a rock shaft 8 carrying rigid crank arms 14 operatively connected with the upper ends 9 of the rods 6^a. Thus the rocking of the rock shaft 8 causes the raising and lowering of the upper part 6 of the workholder. The rock shaft 8 is rocked by a crank arm 10, on the latter, as shown in Figs. 1 and 6; the crank-arm 10 being connected by a link 11 to one end of a bell-crank lever 38 on the rock shaft 12^a; the bell crank lever 38 is connected by a link 37, with a crank arm 36^a on the rock shaft 36.

The lower part 7 of the work holder consists of a box-like part carried by the cross-head 7^a reciprocating in the guides 96, mounted on the frame of my machine. On the crank shaft 12^a, on which the lever 38 is mounted, which operates the upper part of the workholder, is a crank-arm 12, see Figs. 1 and 4, connected by a link 13 with the cross head 7^a. Thus the rocking of the rock-shaft 12^a causes the synchronous operation of the upper and lower parts of the work-holder.

While the work-holder is still in its open 105 position the blanks carried by the lower and upper trays are held in place by clamps 16 and 17, as illustrated by Figs. 3 and 4.

On the piece 6^d (see Fig. 7) are mounted 110 brackets 27^a in which is journaled a shaft 27, on which the clamp 16 is rockably mounted. See details Figs. 17 to 17^d inclusive. The clamp 16 is provided adjacent its middle with angular portions 16^a having a web 16^f provided with an elongated hole 16^e thru which the shaft 27 extends, thus permitting this clamp both a rocking and lineal movement as illustrated by Fig. 17^a. The angular portions 16^a are provided with slots 16^b in the webs 16^d; see Fig. 17. Stirrups 39 extend through said slots 16^b, their lower ends encompass the shaft 27, and springs 40 normally hold the stirrups 39 up. See Fig. 17^a.

On shaft 27 are provided double ended 125 cams 28 located under the webs 16^d of the portions 16^a of the clamp 16, so one end of such cams will strike against said webs 16^d during the rocking of the shaft 27. Thus when the shaft 27 is rocked in one direction 130

the cam 28 will swing the clamp 16 in its position shown by dotted outline in Fig. 17^a, when rocked in the opposite direction said cam 28 will place this clamp in its clamping position as shown by Fig. 17^c; in this position its lip 16^c will clamp the forward edge of the blank 81, carried by the upper tray, on the forward edge of the plate 6^c of the upper part 6 of workholder; and 10 when the cam is in neutral position, that is not performing either action, then the reaction of springs 40 will throw this clamp into its releasing position as shown by Fig. 17^a.

15 The shaft 27 is rocked by the rotation of the crank arm 18 on the shaft 18^a (see Figs. 1 and 23) to which is connected the rod 19^a connected to a crank lug of the rock shaft 20 connected by an arm 21 to a rod 20 22 with the crank arm 23, on the rock shaft 24 journaled in brackets 24^a mounted on the piece 6^a, which carries at its lower end a segmental bevel pinion 25 meshing with a similar pinion 26 on the rock shaft 27.

25 The rock shaft 18^a is rocked by the arm 18^b which forms a double-ended crank with arm 18; the member 18^b of the latter being operatively engaged with the cam 116 as shown in Fig. 23.

30 The devices operating the lower clamp 17, carried by the lower part 7 of the workholder consist of the following:

The frame of the machine includes vertical guides 96, see Figs. 1 and 7, in which 35 slides a cross head 7^a provided with journal bearings 69 (see also Fig. 4^c) in which is journaled a rock or crank shaft 35, provided with cams 35^a at its ends. The clamp 17 consists of a bar made with a lip 76 and 40 provided at its ends with portions 97 having flanges 98. Said portions 97 are made with elongated holes 17^b to receive the crank shaft 35, the clamp 17 pivoting on the latter. The reciprocable cross-head 7^a is provided 45 at each of its ends with a lug and stud 41^a, the flanges 98 of the side portions 17^a of the clamp 17 are provided with similar devices 99, see Fig. 7; and between such devices are secured springs 41. The crank 50 shaft 35 has an arm 100 connected by a link 34 to a crank-arm 33 on the crank-shaft 32 which is rocked by the meshing segmental pinions 31 (see Fig. 1) one of which is on a rock shaft 30 provided with an arm 29 55 connected by rods 19^a and 19 with the crank-arm 18, which also actuates the upper clamp 16 as already stated.

When the crank shaft 35 is rotated in one direction the clamp 17 will be thrown in 60 its releasing position as shown by Fig. 3 and when rotated in the opposite direction this clamp will be thrown in its clamping position, as shown by Fig. 4.

Normally the piece *o*, fastened in the 65 lower tray *g*, rests on the bottom of the lat-

ter, and so remains until the trays *f* and *g* have been introduced into the work holder (consisting of parts 6 and 7, see Fig. 3) by the forward movement of the carriage. The fingers *o*^a of the piece *o* will ride on the 70 sides of the box-like lower part 7 of the workholder, while the plate *g*^a on which the blank lies will drop so as to rest its forward end on the bottom of the part 7. It will be noted from Fig. 22 that the lower 75 tray *g* has slots *g*^a cut away at its sides so that the side wall portions of the lower work-holder may project thru these slots, not interfering with the drop of the tray plate but causing the fingers *o*^a of the piece 80 *o* to ride on the sides of the lower workholder. In this way is produced a sag in the blank carried by the lower tray, spacing it at its middle part from the blank carried by the upper tray so that the hook 85 17 can grip the forward edge of the blank.

The rockable plate *p* functions to lift the forward edge of the blank carried by the upper tray into such position that it can be gripped by the clamp 16 carried by the 90 upper part 6 of the work-holder; see Figs. 3 and 5^a; the required rocking of the plate *p* being effected by the moving of the upper part (6) of the work-holder toward the tray *f*, into their positions in Fig. 4; the 95 resulting movement of the plate *p* being illustrated by Fig. 5^a.

In order to hold the blanks firmly in place in the workholder, while the edges of the blanks are sewed together, the plate 6^c of the upper part of the workholder is provided on three sides with a rib 77 and the upper faces of the corresponding three sides of the lower part of the workholder are provided with a groove 78 to receive said rib; thus when the 100 two parts of the workholder are brought together they will firmly clamp between them, the edges of the blanks. The sewing of said edges is accomplished by devices comprising the rack *a'*, shown in Fig. 1, said devices being similar to the ones described with reference to the same operation in my said previous patent, and because such devices do not constitute a part of my present invention, I refer to my said patent for a description of said devices.

The hollow shaft 60 is provided with a crank arm 63 connected by a link 62 to a bell-crank 61 carried by a rock-shaft 103; the bell-crank 61 being operatively engaged with the cam 104, (as shown in Fig. 23.) On the upper end of the post 66 is mounted a crank arm 53 connected by a link 52, as shown at 110 52^a (Fig. 1,) to a crank arm 51, as shown at 52^b, said crank arm being carried by a rock shaft 50, having at its lower end a crank-arm 49 connected by a link 48 to crank 47 mounted on a rock shaft 105 also operatively connected with said cam 104 as shown in Fig. 23. On the posts 66 and 66^a, below the 115

rod 65, are rigid crank arms 55 and 55^a, approximately positioned at right angles to each other as shown in Fig. 8, the latter crank-arms being connected by a link 56.

5 The fuller 42 consists of the parts shown in Figs. 7, 8, 9 and 10.

On the piece 6^a of the upper work holder are provided two bracket arms 102, having vertical hinge pins 66^a, 66^c. On the latter 10 are supported the posts 66 and 66^a which have both arcuate and vertical movement. The said posts are connected at their upper ends by a rod 65, the ends of which are adapted to permit said posts to be rotated, as 15 shown at 66^b and 66^c in Fig. 7. The rod 65 is connected by arms 64, and 64^a with arms 59, 59^a which are part of the hollow rock shaft 60, see also Fig. 1, which is rotatably mounted on the rock shaft 8 as shown in the 20 latter figure. The lower ends of the posts 66, 66^a are provided with arms 57 and 57^a (see also Fig. 1^a).

43 and 43^a are the extension arms of the fuller 42. They are connected by a bar 44 25 so that one is relatively slidable on the other in order that these arms may be extended, that is, placed in their position in Figs. 8 and 9, and moved again apart as shown in Fig. 9. The extension arms 43, 43^a are provided with brackets 101 and 101^a, respectively, by which they are supported on the crank arms 57 and 57^a, as more clearly shown in Fig. 1^a. The brackets 101 and 101^a have mounted on them other brackets 107 and 108 30 respectively; the bracket 107 is provided with a tube 45, and the bracket 108 is provided with a rod 46 which slides in said tube 45. On the pins 58 and 58^a are mounted sleeves 110 as shown in Fig. 24 which sleeves 35 are integral parts of the arms 57 and 57^a; and on the upper ends of the pins 58 and 58^a are threaded nuts 109, in this way holding the brackets 106 firmly extended. By rotating the hollow shafts 66 and 66^a the 40 arms 57 and 57^a of the fuller are swung in and out as are the extension arms 43 and 43^a which enter the hollow of the lower box-like workholder part; and when introduced in said lower workholder part the extension 45 arms 43 and 43^a are projected laterally as shown in Fig. 9, thereby producing the required fullness in the blank carried by the lower tray. When the latter step has been 50 performed the fuller is withdrawn from the workholder, the seam 82 is sewn and gripping members 67, 68 and 67^a, 68^a are thrown into action as diagrammatically illustrated in Fig. 19 for the purpose of removing the cuff and turning the same right side out, 55 this step and the devices performing the same being fully described in my said preceding patent.

60 The several working parts of my machine are connected to a prime mover so as to operate synchronously; such cooperating means

being shown sufficiently by Figs. 1 and 23 in connection with the other views to enable any skilled mechanic to build my machine.

The bracket arms 101, 101^a carrying the extension arms 43 and 43^a of the fuller are 70 further held in alinement by a guide arm 121, a rigid part of the bracket 101, and having a sliding connection with the bracket arm 101^a.

The successive steps performed in the 75 operation of my machine are as follows:

Assuming that a blank has been placed in each of the trays *f* and *g*, the first step is the 80 forming of the fold 84 in the blank carried by the lower tray *g*.

Recapitulating in part the devices performing this step: The rods *s*, and *s'* are at the near side connected at their lower ends to the bell crank 2^b. The said lower ends are preferably connected by a cross rod 117. The lower end of the rod *s'* is connected to the bell-crank 2^b, rigid on a rock shaft 118. On the far side of the latter is carried a crank-arm 2^b which is connected to the rod *s*. See Fig. 1.

90 On the ends of said cross-rod 117 are mounted bell-cranks 3; said bell cranks are connected to the lower ends of the rods *t*, *t'*, the latter operating the presser as above described. The bell-cranks 3 are yieldingly connected by rods 111 with the springs 112, and with levers 120 mounted on rock shafts 113, one arm of each being engaged with the cam 104.

The fold 84 having been formed as above 100 described, and the ironing bar *q*, and therewith the presser *r* having been lifted clear of the lower tray, the carriage *e* is moved forward. The carriage is reciprocated by the rod *e* which has a cam arm 115 engaged 105 with the cam 116. See Fig. 23.

During the forward movement of the carriage the lower tray *g* is relatively moved forward so as to become alined with the upper tray *f* as above described; the trays being moved in this wise into the work holder. After the trays have entered the workholder, the upper and lower parts 6 and 7 of the latter are moved slightly together; thereby bringing the upper part 6 of the workholder to bear on the plate *p* carried by the upper tray, and rocking such plate thereby lifting the forward edge of the blank carried by the upper, and placing such edge in 115 position for being seized by the clamp 16 120 carried by the upper part of the workholder.

Simultaneously the movement upward of the lower part 7 of the workholder places said box like lower part in position for receiving the blank carried by the lower tray *g* so that the forward edge of such lower blank may be clamped by the clamp 17 carried by the lower part 7 of the workholder.

Furthermore, simultaneous with said movements of the workholder parts, the 125 130

fuller 42 is introduced between the spaced blanks carried by said trays.

Next the movement of the carriage is reversed thereby withdrawing the said trays 5 from the work-holder. Next the upper and lower parts of the work-holder are moved together into their position.

The upper work-holder has a tongue 77 and the lower has a corresponding groove 10 78 around three sides of each of the parts 15 of the work-holder. The moving of the work-holder parts, together cause the blank to be gripped by this tongue and groove arrangement and thus the parts are held 20 against any relative movement. Fuller member can then be withdrawn and the seam 25 82 may be sewn.

The described movements of the parts of the work-holder and of the fuller are caused 20 by the following devices:

The upper and lower work-holder parts are actuated by the rock shaft 12^a, which is 25 rocked by rod 37 connected to bell crank 36^a which is mounted on a rock shaft 36, 30 see Figs. 6 and 23, one arm of the bell crank 36^a being engaged with the cam 104.

The fuller is operated thru the medium of the rod 62, as above described, and the latter 30 rod is connected to bell-crank 61, mounted on rock shaft 103, one arm of the said bell 35 crank 61 being engaged with the cam 104. See Figs. 1 and 23.

The further operations of my machine are merely repeating the steps of my said preceding patent; the cam 122 shown in Fig. 23 35 actuating the movement of the cuff turning devices, included in the mechanism last referred to, and of which cuff turning mechanism the parts, 67, 67^a and 68, shown in Fig. 40 19 are a part.

Motion is imparted to the gear 123 from a prime mover, and the pinion 124 meshing with said gear operates the cam 116. The cam 104 is carried by the shaft 125 of the 45 gear 123.

I claim:

1. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart from each other.

50 55 60 65 66

2. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart from each other, means on the work-holder parts for gripping the blanks respectively, means for retracting the carriage and therewith the trays, means for producing full-

ness in one of said blanks while in the work-holder, the latter means being inserted into the work-holder in time with the withdrawal of said carriage, means for moving said work-holder parts together thereby holding 70 the blanks in the work-holder while sewing their edges together, means for withdrawing said fullness-producing means after the blanks have been clamped by the work-holder.

75 80 85 90

2. In a machine of the character described, a carriage, trays supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically.

95 100 105 110

3. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other.

115 120 125 130

4. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart from each other.

5. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart from each other, means on the work-holder parts for gripping the blanks respectively.

6. In a machine of the character described,

- 5 a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart 10
- 15 from each other, means on the work-holder parts for gripping the blanks respectively, means for retracting the carriage and therewith the trays.
7. In a machine of the character described, 20 a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart 15
- 25 from each other, means on the work-holder parts for gripping the blanks respectively, means for retracting the carriage and therewith the trays, means for producing fullness in one of said blanks while in the work-holder, the latter means being inserted into the work holder in time with the withdrawal of said carriage, means for moving said work-holder parts together thereby holding the blanks in the work-holder while sewing their edges together.
- 30 8. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart 35
- 35 from each other, means on the work-holder parts for gripping the blanks respectively, means for retracting the carriage and therewith the trays, means for producing fullness in one of said blanks while in the work-holder, the latter means being inserted into the work holder in time with the withdrawal of said carriage, means for moving said work-holder parts together thereby holding the blanks in the work-holder while sewing their edges together.
- 40 9. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart 45
- 45 from each other, means on the work-holder parts for gripping the blanks respectively, means for retracting the carriage and therewith the trays, means for producing fullness in one of said blanks while in the work-holder, the latter means being inserted into the work holder in time with the withdrawal of said carriage, means for moving said work-holder parts together thereby holding the blanks in the work-holder while sewing their edges together.
- 50 10. In a machine of the character described, a work-holder provided with means for holding the blanks spaced from each other and a fuller for producing fullness in one of said blanks while in the workholder, means carried by said workholder for holding said blanks in position with the fullness so produced and other means for withdrawing said fuller, the latter timed to act when said fullness holding means engage said blanks.
- 55 11. In a machine of the character described, comprising a workholder composed of upper and lower vertically movable parts, means for moving such parts towards and from each other, means on the workholder parts for gripping the blanks and holding them spaced apart, and a fuller for producing fullness in one of said blanks while in the workholder, and a rib provided on one of said workholder parts and a corresponding groove on the other of said parts to hold said blanks in position with the fullness so produced and to permit the withdrawal of said fuller without affecting said fullness.
- 60 12. In a machine of the character described, comprising a workholder composed of upper and lower vertically movable parts, means for moving such parts towards and from each other, means on the workholder parts for gripping the blanks and holding them spaced apart, and a fuller for producing fullness in one of said blanks while in the workholder, and a V-shaped rib provided on one of said workholder parts and a corresponding groove on the other of said parts to hold said blanks in position with the fullness so produced and to permit the withdrawal of said fuller without affecting said fullness.
- 65 130

- blanks in the work-holder while sewing their edges together.
9. In a machine of the character described, a carriage, trays, supported by the carriage, for holding blanks, such trays lying in spaced apart horizontal planes, one tray being in advance of the other, means for forming a fold on the forward edge of the blank carried by one of said trays, means for advancing one tray relatively to the other, thereby to align the trays vertically, a work-holder comprising upper and lower vertically movable parts, means for moving such parts towards and from each other, means for moving the carriage forward thereby to insert the trays between the upper and lower parts of the work-holder while spaced apart 70
- 75 from each other, means for moving said work-holder parts together thereby holding the blanks in the work-holder while sewing their edges together.
10. In a machine of the character described, a work-holder provided with means for holding the blanks spaced from each other and a fuller for producing fullness in one of said blanks while in the workholder, means carried by said workholder for holding said blanks in position with the fullness so produced and other means for withdrawing said fuller, the latter timed to act when said fullness holding means engage said blanks.
- 100 11. In a machine of the character described, comprising a workholder composed of upper and lower vertically movable parts, means for moving such parts towards and from each other, means on the workholder parts for gripping the blanks and holding them spaced apart, and a fuller for producing fullness in one of said blanks while in the workholder, and a rib provided on one of said workholder parts and a corresponding groove on the other of said parts to hold said blanks in position with the fullness so produced and to permit the withdrawal of said fuller without affecting said fullness.
- 105 115
12. In a machine of the character described, comprising a workholder composed of upper and lower vertically movable parts, means for moving such parts towards and from each other, means on the workholder parts for gripping the blanks and holding them spaced apart, and a fuller for producing fullness in one of said blanks while in the workholder, and a V-shaped rib provided on one of said workholder parts and a corresponding groove on the other of said parts to hold said blanks in position with the fullness so produced and to permit the withdrawal of said fuller without affecting said fullness.
- 110 120
- 125 130

13. In a machine of the character described, a work holder comprising upper and lower parts, means for moving said parts relatively towards and from each other, a releasable clamp on said upper work holder part, a blank holding tray arranged to enter said workholder prior to the closing of said workholder, said tray having a rockable plate in the bottom thereof adapted to be engaged by the downward movement of the upper workholder part so as to lift the blank carried thereby into position for engagement by the clamp upon the upper workholder.
14. In a machine of the character de-
scribed, a workholder comprising upper and lower parts, means for moving said parts relatively towards and from each other, means for inserting blanks to be operated upon into such workholder, said workholder parts having opposed perimetric flanges substantially encompassing the same, and co-operating rib and groove engaging portions upon the opposed faces of the said flanges, adapted to hold the blanks against displacement in said workholder after the same has been closed.

OMAR A. WHEELER.
